UNITED STATES PATENT OFFICE.

JAMES A. LIGHTHIPE, OF PHILADELPHIA, PENNSYLVANIA, ASSIGNOR TO HIMSELF, GEORGE W. BRATTON, OF SAME PLACE, AND HENRY NUNEZ, OF NEW YORK, N. Y.

ARC LAMP.

SPECIFICATION forming part of Letters Patent No. 408,887, dated August 13, 1889.

Application filed June 19, 1888. Serial No. 277,565. (No model.)

To all whom it may concern:

Be it known that I, JAMES A. LIGHTHIPE, a citizen of the United States, residing in the city and county of Philadelphia, and State of Pennsylvania, have invented a new and useful Improvement in Regulators for Electric-Arc Lamps, of which the following is a specification.

My invention relates to improvements in arc-light regulators of that type in which the upper carbon is fed forward by gravity and its descent is governed by a rack and pinion controlled electro-magnetically. Its objects are, first, to provide such a regulator as will be steady and regular in the feed of the carbon; second, to provide a novel form of electro-magnetic cut-out for automatically cutting the lamp out of circuit in the event of any abnormal separation of the carbons or accident to the feeding-gear. I accomplish these objects by the mechanism hereinafter described, but particularly pointed out in the claims which follow this specification.

Referring to the drawings for a full understanding of my invention, Figure 1 represents a side elevation of my improved regulator, showing the feed-regulating magnet in broken section; and Fig. 2 represents an end elevation of the apparatus.

T is the carbon-sustaining rod, guided in the usual manner through the frame and provided with a rack S.

G is a tilting feeding-frame pivoted at E F on the side of the lamp-frame. This tilting frame carries one or more armatures H H, located below the polar extensions D D of magnet C, and also two revolving shafts L M, the former of which is held in place by adjustable screws J J and the latter by screws K K.

On the shaft L is a faradic disk N of magnetic material, which is adapted to rotate between the lateral faces of the magnet's pole-pieces D D. The disk and shaft are geared through pinion P and cog-wheel Q to the second shaft M, which carries also a second pinion R, meshing with a rack S of the carbon-carrier T. The cog-wheel Q is loose on shaft

M, and is connected by a spiral spring m with the tilting frame G. Said cog-wheel carries a pawl p, which takes in a ratchet W, fixed to the shaft M.

U is an adjusting-spring connected with the free end of the tilting frame at one end and at its other end to a bell-crank lever V, pivoted to the frame and having an adjusting-screw W' for regulating its stress, and hence the length of the arc.

The regulating-magnet C is pivoted to a block of metal B, fixed to the top of the lamp-frame, thereby guaranteeing equal action on the part of the pole-pieces D D and faradic disk N. The coarse wire X, wound directly about the core of the magnet C, is connected at one end to the plus binding-post Y, which is insulated from the frame, the other end thereof being connected to the upper-carbon holder in the usual way, making a passage for the current through the upper carbon, thence to the lower carbon, finally to the frame, and by the standard S' and wire t to the minus binding-post Y'.

Z is a fine wire of high resistance differentially wound, in a manner well understood, about the coarse wire X on magnet C, connected at one end to binding-post Y and at the other to the fine-wire coil B', joined to the cut-out apparatus and the binding-post Y', being in the nature of a high-resistance shunt around the lamp, the function of which is well understood by those skilled in the art. The coil B', already described as being in the derived circuit and of high-resistance wire, is fixed to the frame by arms or standards C' C', which latter also carry on a rod joining them a pivoted armature D', having an adjustable weight F' on its lower end E', as well as a metallic or conducting arm G', adapted when drawn up under action of the magnet B' and armature D' to close a local or shunt circuit about the lamp from the plus binding-post Y by wire O through standard C', lever G', spring L', wire U', low-resistance magnet J', through the negative binding-post Y'. This energizes both armatures M' and causes them to firmly grip the lever G' between the springs

L' L², making a firm electrical contact through the shoulder N' of spring L' and with lever G'.

The operation of this cut-out is at once obvious and needs no further description here.

The operation of the lamp is as follows: The current passing from the plus binding-post Y through magnet C, carbon-carrier T, and upper and lower carbons (latter not shown) 10 to and through standard S' by wire t to the negative binding-post Y' causes the armatures H H to lift the tilting frame G, and with it the pinion R, as well as the carbon-carrier T, thereby establishing the arc between the carbons, and also magnetizing the faradic disk N in such manner as to prevent its rotation. As the pinion R is raised the carbon-carrier T is lifted, the spiral spring m having been put under stress through pawl p and 15 ratchet W when the carbon-carrier T was inserted. This gives a delicate and sensitive adjustment of the carbon-feeding apparatus and prevents sudden and irregular jerks due to most gravity feeding devices. The spring 20 m aids gravity in feeding the carrier forward. As the arc becomes abnormal the current passes into the derived circuit Z in a manner well understood, and the magnet becomes less energetic, thus allowing the faradic disk N 25 to rotate under stress of the carbon-carrier and spring m, thereby permitting the carbon to descend until a normal current is again attained in the arc circuit, when the frame is again drawn up. When the upper carbon is 30 first inserted in the lamp and the rack placed at its uppermost position, the spring m is under the strongest tension tending to aid gravity in forcing the carrier forward; but this influence is always counteracted by the action 35 of the faradic disk N acting through the train of gear as long as the arc is normal.

I am aware that it is old in the art to provide gravity-feed arc lamps with tilting frames carrying a train of gear and a pinion 40 which meshes with a rack on the carbon-carrier, by which the arc is established and regulated through the agency of a differentially-wound magnet or magnets; and I do not therefore claim, broadly, such a construction.

I am also aware that it is old to provide an 50 arc lamp with an automatic electro-magnetic cut-out which acts through the derived circuit to close a circuit of low resistance about the lamp and through a low-resistance electro-magnet which holds said low-resistance 55 shunt-circuit permanently closed as long as the current flows, and I do not therefore claim, broadly, this feature.

I am also aware that it is not novel with me to regulate the feed of the electrodes in 60 an arc lamp through the agency of a faradic disk operatively connected to a train of gearing and the electrode or electrodes, and I make no claim to the application of this generic principle; but 65

What I do claim, and desire to secure by Letters Patent of the United States, is—

1. An arc-light regulator having a carbon-carrier geared to a train of gearing attached to a pivoted frame carrying a rotating armature located in the magnetic field of a pivoted regulating electro-magnet, between the poles of which the rotating armature rotates, in combination with fixed armatures carried also by the frame and lying in the magnetic 70 field of the regulating-magnet, substantially 75 as described.

2. An arc-light regulator consisting of a carbon-carrier geared to a train of gearing carried on a pivoted frame, and also to a rotating armature located in the magnetic field of a regulating electro-magnet, with a fixed armature also attached to said frame and located in the magnetic field for establishing the arc, substantially as described. 80 85

3. In an arc-light regulator, the combination of a pivoted frame carrying a train of gear geared to a rack on the carbon-carrying rod, and a rotating armature located between the poles of a regulating-magnet, with a fixed 90 armature attached to said frame, whereby the arc is established and regulated, substantially as described.

JAMES A. LIGHTHYPE.
